United States Patent Office

Des. 213,230
Patented Jan. 14, 1969

213,230

TYPEWRITER

Carl Auboeck, Vienna, Austria, assignor to Olympia
Werke A.G., Wilhelmshaven, Germany

Filed Feb. 1, 1968, Ser. No. 10,413

Claims priority, application Germany Sept. 4, 1967

Term of patent 7 years

U.S. Cl. D64—11
Int. Cl. D18—01

Fig. 1

Fig. 2

Fig. 3

FIG. 1 is a perspective side view;
FIG. 2 is a perspective rear view; and
FIG. 3 is a perspective front view of my new design
for a typewriter.

The essential features of the design reside in the portions shown in full lines on the drawing conventional keys and other elements being shown in broken lines in all the views.

I claim:

The ornamental design for a typewriter, substantially as shown and described.
